UNITED STATES PATENT OFFICE.

EDWIN C. BRUEN, OF BROOKLYN, NEW YORK.

DEVICE FOR PRODUCING THE REPRESENTATION OF A SNOW-STORM.

No. 901,319.

Specification of Letters Patent.

Patented Oct. 20, 1908.

Application filed October 19, 1907. Serial No. 398,173.

To all whom it may concern:

Be it known that I, EDWIN C. BRUEN, a citizen of the United States, and resident of Brooklyn, in the county of Kings and State 5 of New York, have invented a certain new and useful Improvement in Devices for Producing the Representation of a Snow-Storm, of which the following is a specification.

My invention relates to a novel amusement device particularly designed for use in 10 connection with Christmas trees.

The main feature which characterizes my invention resides in mechanical means for producing an artificial snow storm, or in 15 other words the representation of a snow storm.

My invention also includes details of construction and operation all as hereinafter described and pointed out in the claims 20 concluding this specification.

In the accompanying drawing illustrating my invention in the several figures of which like parts are designated by similar letters of reference, Figure 1, is a perspective view of a Christmas tree having my invention applied thereto. Fig. 2, is a side view in elevation and partly in section of the device embodying my invention, and Fig. 3, is an enlarged detail view of one of 30 the artificial snow flakes I prefer to employ. Fig. 4, is a side view partly in section of a modification.

Referring particularly to Figs. 1 and 2, A designates a box or receptacle preferably 35 made in the shape of a bird-house. The receptacle A, is provided with an upper cross-bar B, and lower cross-bar C, these bars extending across the interior of the receptacle A, and being secured to the side walls 40 D, D', thereof in any appropriate manner.

A vertical shaft E, is centrally mounted in the receptacle A, the upper end of this shaft passing through a suitable opening in the upper cross-bar B, and being secured in 45 place by the ring F; the lower end of this shaft passes through a similar opening in the lower cross-bar C, and is provided with a laterally extending flange G, which rests on top of the bar C. These openings through 50 the cross-bars constitute in effect the bearings for the shaft E, when a rocking motion is imparted to the latter as hereinafter described. As shown the shaft E, is a hollow or tubular shaft closed at its upper end, and 55 having in that part of its lower end extending below the receptacle A, a series of per-

forations H. Near the lower end of the shaft and above the bar C, a sleeve I is keyed to the shaft and a plurality of rods or projections J, are fixed to this sleeve and extend 60 therefrom radially within the receptacle A. Any desired number of these projections may be employed.

K, designates a curved rod rigidly connected to the shaft E, near the top thereof 65 and below the cross-bar B, the rod K, extending upwardly and outwardly and preferably terminating in an enlarged end K'. As shown the end K' of the rod K, is in contact with an air bellows L. The bellows 70 L, is secured in place to the side wall D', of the receptacle A, in any suitable manner, and from this bellows a rubber tube M, extends downwardly and is connected to the upper end of a tube N, the lower end of 75 which is attached to the upper end of and leads into the hollow standard O. A rubber tube M', is secured to the lower end of the standard O, and thence extends and is connected to an air pump P, or other suitable air forcing apparatus. The receptacle A, is rigidly mounted upon the standard 80 O, by means of the curved arms Q, which are respectively attached by suitable means to the standard O, and side walls of the 85 receptacle A. The bottom of the receptacle A, preferably consists of a wire netting or screen R, which acts as a sieve for the contents thereof as I will presently describe. A mechanical or toy bird S, may 90 be mounted in any appropriate manner on top of the standard O, and a portion of the air ascending through the standard O, be communicated to the bird S, by means of the tube T. Instead of the bird S, any other 95 appropriate toy actuated by air pressure may be employed.

In the modification of my invention shown in Fig. 4, the standard O, and parts connected therewith are omitted, and the receptacle A, is inclosed by a globular shaped shield U, and both are suspended from an over head wire V, by hooks or eyes W. In this construction the tube M, passes upwardly through the top of the receptacle A, 100 over the wire V, and is led directly to the air pump P, which may be located at any desired point.

Referring to Figs. 1 and 2, the receptacle A, being mounted in the top of a Christmas 110 tree X, by wiring or tying the standard O, to the tree, or attaching the same in any other

convenient manner, the operation of this device is as follows: The receptacle A, being filled with finely cut white paper such, for instance, as what is known as confetti, the air pump P, is operated to force a current of air through the tube M', standard O, tube N, and tube M, to the bellows L, thereby expanding the latter. With each expansion of the bellows L, the latter moves the rod K, 5 thus rotating and imparting a rocking motion to the shaft E; with each rotation of the shaft by the means just described a spring Z, coiled around the shaft E, one end of which is secured to said shaft, and the other to the bar B, is tensioned and acts to rotate or rock the shaft in the opposite direction as the air leaves the bellows L, and the latter collapses. The shaft is thus alternately rocked 10 first in one direction and then in the other 15 as long as air is forced into the bellows L. As the shaft rotates to and fro the radial projections J, separate and disintegrate the mass of paper or confetti, and with each rocking or rotation of the shaft a shower of 20 the paper particles or confetti will fall through the openings in the netting or screen R, and drop or float downwardly like a natural fall of snow. The air escaping from the bellows L, as the latter collapses, 25 passes by means of a tube M², into and down the shaft E, and then outwardly in jets through the perforations H, serving the purpose of blowing the paper particles in different directions and thus enhancing the snow 30 storm effect. As the device is in operation a portion of the air current ascending through the standard O, can be utilized by means of the small tube T, to cause the toy bird S, to 35 whistle thus simulating the singing of a natural bird.

In the modification shown in Fig. 4, the construction and operation of my device is the same as shown in Fig. 2, excepting that the standard O, arms Q, tube N, bird S, and 40 tube T, are all omitted and the tube M, is carried upwardly through the top of the receptacle A, over the wire V, and thence to the pump P, as stated. In this modified construction the receptacle A, when used in connection with a Christmas tree is to be suspended by means of the wire V, above the tree, and this wire may be stretched from one wall to the other in a room and secured at each end to the picture molding, or to hooks, 45 or in any convenient manner. Instead of using the wire V, the device may be suspended directly from a ceiling hook.

When the modified form of my invention is employed it may also be used to send out 50 showers of confetti in a ball room, or it may be utilized in connection with masquerade parties, carnivals, children's parties, theatrical exhibitions etc. I prefer to use in connection with my device confetti of the boomerang shape in general outline as shown in

the enlarged view Fig. 3, as I have found in practice that paper particles or confetti of this shape are quickly affected by air currents and thus float downwardly to a certain extent like falling snow.

In the manufacture of this device any materials suitable for the purpose may be employed and, therefore, I do not think it necessary to describe the same.

The receptacle A, standard O, and shield U, may be painted or otherwise attractively decorated. For instance to give the effect of a winter scene, the receptacle A, and shield U, may be varnished and coated with mica and be provided with artistically arranged imitation icicles. As shown the shield is provided with a tassel like fringe which may be in different colors to give an attractive finish.

The receptacle A, and shield U may be of any desired shape, and instead of a bottom 85 R, composed of a wire netting or screen, the bottom may be made of other material and provided with openings or perforations there-in suitable for the purpose.

It is obvious that instead of the rods J, 90 projections from the shaft E of any desired shape or configuration may be employed provided they answer the purpose of separating the mass of paper particles or confetti.

What I claim as my invention and desire 95 to secure by Letters Patent is:—

1. In a device for producing the representation of a snow storm a receptacle provided with a perforated bottom and containing particles of material representing snow flakes 100 a vertical shaft mounted in said receptacle, a plurality of fixed projections on said shaft, and means for automatically rocking said shaft first in one direction and then in the opposite direction, substantially as described. 105

2. In a device for producing the representation of a snow storm a receptacle for material representing snow flakes, a sieve like bottom for said receptacle, a vertical shaft mounted in said receptacle, a plurality of 110 fixed projections on said shaft, a fixed rod extending from said shaft, an air bellows in contact with said rod, means for expanding said bellows to impart motion to said shaft in one direction and a spring to move said 115 shaft in the opposite direction, substantially as described.

3. In a device for producing the representation of a snow storm a receptacle for material representing snow flakes, a sieve like 120 bottom for said receptacle, a hollow vertical shaft mounted in said receptacle and having a series of perforations in its lower end, a plurality of fixed projections on said shaft, a fixed rod extending from said shaft, an air 125 bellows in contact with said rod, means for forcing an air current through said bellows to expand the same thereby imparting motion to said shaft in one direction and a spring to move said shaft in the opposite direction 130

when said bellows collapses, the said air current passing outwardly through the perforations in the end of said shaft, substantially as described.

- 5 4. In a device for producing the representation of a snow storm a receptacle provided with a sieve-like bottom and containing paper particles, a supporting standard for said receptacle, a vertical shaft mounted in said receptacle, a plurality of projections extending from said shaft and means for auto-

matically rocking said shaft first in one direction and then in the opposite direction, substantially as described.

Signed at New York city, in the county ¹⁵ and State of New York, this 15th day of October A. D. 1907.

EDWIN C. BRUEN.
